CONDENSATE TRAP FOR SUCTION CONDUITS

Frank B. Allen, Verona, N. J., assignor to C-O
Two Fire Equipment Company, Newark, N. J.,
a corporation of Delaware

Application October 9, 1942, Serial No. 461,641

2 Claims. (Cl. 137—69)

This invention has reference to water traps adapted for use with systems or apparatus comprising tubes or pipes through which air or gas is being drawn by suction.

In smoke detecting apparatus of the type employed in detecting smoke in different compartments on a ship and/or in delivering of fire extinguishing fluid to such compartments, provision is made for continuously drawing air from the compartments through tubes or pipes. If high temperature air is drawn from the compartments it may carry a large amount of moisture and if the tube passes through a very cold or through a cooler section, the moisture in the air will drop out and flow to the lowest point in the tube. The amount of moisture so collected may decrease the effective cross sectional area of the suction tube thereby decreasing the efficiency of the detecting system or it may close the suction tube thus defeating the whole purpose of the system and there are other obvious objections to the collection of water in the tubes. Condensate traps have been provided for the purpose of trapping the condensed moisture and letting it escape and these traps have been provided with means for preventing the escape of fire extinguishing fluid under pressure from the tubes into and through the condensate trap and out into the atmosphere.

It is an object of this invention to provide an improved form of condensate trap for suction tubes, of a simpler form than has heretofore been known and in which the parts are readily assembled and may be readily disassembled for purposes of inspection, cleaning and replacement.

Other objects of the invention will appear from the following description taken in connection with the single figure of the drawing which is a vertical axial section of the condensate trap in position on a tube.

The condensate trap comprises a cylindrical casing 2 which is preferably made of brass and which is provided with a bore extending from one end of the casing to the other. This bore comprises an upper section 3 of relatively large diameter and of greater length than the other sections of the bore, a second section 4 of smaller diameter and of shorter length, a third section 5 of still smaller diameter and a fourth section 6 of still smaller diameter.

Seated in the section 3 of the bore and on the shoulder 10 between sections 3 and 4 is a porous ceramic core 11 preferably cup-shaped as shown and held seated against said shoulder by means

of a phosphor bronze spring 12 having its upper convolution 13 enlarged to seat in a groove 14 near the upper end of the wall of the section 3 to retain the spring in position which in turn retains the ceramic core in position.

In the section 4 of the bore is mounted a valve 16 in the form of a disc held in an intermediate position in the section and spaced from the shoulder 17 between the sections 4 and 5 which shoulder is fashioned to constitute a seat for the valve. The valve 16 is held in this position by a spring 19 preferably of phosphor bronze seated in the section 5 and on the shoulder 20 between the sections 5 and 6 of the bore. The valve 16 is of slightly less diameter than the diameter of the section 4 to permit condensed water passing through the ceramic core to drain past the valve 16 but is of sufficiently large diameter to cause gas such as carbon dioxide gas passing through the core to build up sufficient pressure to seat the valve 16 on the valve seat 17 to prevent further escape of such gas as when the tube to which the trap is connected is used for conveying fire extinguishing fluid to the room or compartment in which smoke has been detected.

The trap casing 2 may be connected by means of a T connection, not disclosed, to the tube or provision may be made for connecting the casing to the tube without necessitating cutting the tube and connecting a T connection therein.

For this purpose the upper end of the casing 2 may be threaded exteriorly as indicated for threaded connection in the interiorly threaded end of a boss on a lower clamping member 25 which may be drawn up against the tube by means of threaded bolts 26 threaded into an upper clamping member 27 as is well understood.

For the purpose of establishing communication between the casing and the tube, the lower member 25 is provided with a bore 28 having a shoulder 29 on which is seated a sleeve 30 which extends into a hole drilled in a low point in the tube in which water collects. A gasket 31, preferably of material known as "Vellumoid," seated in the curved seat in the lower member 25 and surrounding the sleeve 30 is provided to effect a fluid tight connection between the tube and the lower clamping member 25 as is understood.

While I have illustrated and described in detail a preferred embodiment of my invention, it is to be understood that I reserve the right to all such changes and modifications as fall within the principle of my invention and the scope of the appended claims.

I claim:

1. In a condensate trap for suction and high pressure conduits, comprising a vertically disposed casing having provision for supporting the same on the lower side of a conduit and provided with a bore comprising four sections of different diameters arranged in the order of decreasing diameters from the upper to the lower end of the casing and forming three upwardly facing shoulders, a porous element seated on the upper shoulder and of a porosity permitting the escape of condensate but of sufficient fineness of pores to substantially prevent air from being drawn therethrough under suction pressures in said conduit while permitting the passage of gas under high pressure in said conduit in substantial quantities, a light spring seated on the lower shoulder and a valve disc supported by said spring at a point between the upper and intermediate shoulders and of slightly smaller diameter than that of the bore section in which it is located to permit the products of condensation to flow past said valve disc, the porosity of said element, the relative diameters of said valve disc and said bore section, and the strength of said spring being so chosen and proportioned that gas under high pressure will pass through said element in sufficient amounts to seat said valve disc on said intermediate shoulder.

2. In a condensate trap for suction and high pressure conduits, comprising a vertically disposed casing having provision for supporting the same on the lower side of a conduit and provided with a through bore comprising at least three sections of different diameters with the section of the largest diameter located at the upper end of the casing and the section of the smallest diameter located in the lower end of the casing, providing two upwardly facing shoulders, a porous element seated on the upper shoulder and of a porosity permitting the escape of condensate but of sufficient fineness of pores to substantially prevent air from being drawn therethrough under suction pressures in said conduit while permitting the passage of gas under high pressure in said conduit to pass therethrough in substantial quantities, a valve disc located in the center section of the bore intermediate of said shoulders, said lower shoulder constituting a valve seat, a light spring supporting said valve disc raised from said seat, the porosity of said element, the relative diameters of said valve disc and said center bore section and the strength of said spring being so chosen and proportioned that the amount of gas passing through said element under high pressure in said conduit will seat said valve disc.

FRANK B. ALLEN.
